UNITED STATES PATENT OFFICE

168,544

HANGER FOR CLOTHESLINES

Roy L. Hiser, Fort Worth, Tex.

Application June 22, 1951, Serial No. 15,631

Term of patent 14 years

(Cl. D49—1)

To all whom it may concern:

Be it known that I, Roy L. Hiser, a citizen of the United States, residing in Fort Worth, in the county of Tarrant and State of Texas, have invented a new, original, and ornamental Design for a Hanger for Clotheslines, of which the following is a specification, reference being had to the accompanying drawing, forming a part thereof.

Figure 1 is a perspective view of a hanger for clotheslines, showing my new design.

Figure 2 is a broken end elevation of the hanger for clotheslines illustrated in Figure 1.

I claim:

The ornamental design for a hanger for clotheslines, substantially as shown.

ROY L. HISER.
